United States Patent Office

Des. 224,765
Patented Sept. 19, 1972

224,765

CHAIR

James P. Manning, Deerfield, Ill., assignor to Republic
Molding Corporation, Niles, Ill.

Filed Oct. 12, 1970, Ser. No. 25,460

Term of patent 14 years

Int. Cl. D6—02

U.S. Cl. D6—66

FIG. 1 is a plan view of a chair according to my new design;

FIG. 2 is a right side view of the chair of FIG. 1;

FIG. 3 is a front elevational view of the chair of FIG. 1;

FIG. 4 is a bottom view of the chair of FIG. 1;

FIG. 5 is a cross sectional view of the chair of FIG. 1, taken along line 5-5 of FIG. 3; and

FIG. 6 is a back view of the chair of FIG. 1.

The left elevational view of the chair according to the present invention is a mirror image of FIG. 2.

I claim:

The ornamental design for a chair, substantially as shown.
